(57) **CLAIM**

The ornamental design for a case for non-circular CD-ROM medium, as shown and described.

DESCRIPTION

FIG. 1 is a top plan view of the case for a non-circular CD-ROM medium in an open configuration;

FIG. 2 is a cross-sectional view of the open case taken through section line 2—2 of FIG. 1;

FIG. 3 is a close-up view of region 3 of FIG. 2;

FIG. 4 is a close-up view of region 4 of FIG. 2;

FIG. 5 is a close-up view of region 5 of FIG. 2;

FIG. 6 is a bottom plan view of the open case;

FIG. 7 is a top plan view of the case in a closed configuration;

FIG. 8 is a cross-sectional view of the closed case taken through section line 8—8 of FIG. 7;

FIG. 9 is an end elevational view of the closed case, the opposite end being a mirror image thereof;

FIG. 10 is a front elevational view of the closed case; and,

FIG. 11 is a rear elevational view of the closed case.
